UNITED STATES PATENT OFFICE.

FREDERICH W. KUEHN, OF ST. LOUIS, MISSOURI.

WRITING IMPLEMENT.

1,270,035.

Specification of Letters Patent. Patented June 18, 1918.

Application filed October 26, 1917. Serial No. 198,423.

To all whom it may concern:

Be it known that I, FREDERICH W. KUEHN, a citizen of the United States, and residing at St. Louis, in the State of Missouri, have invented new and useful Improvements in Writing Implements, of which the following is a specification.

This invention relates to fountain pens, more particularly to that class of fountain pens adapted to be used for writing or printing signs or posters, or for producing heavy lettering or writing of various styles.

The object of this invention is to produce an improved pen of the above-mentioned class which will be simple and compact in structure, peculiarly adapted for the character of work for which it is constructed, and be at the same time economical in manufacture.

20 My invention contemplates the provision of a novel nib and holder which will readily execute strokes of varying widths and at the same time permit a supply of ink sufficient for the stroke desired.

25 My invention further contemplates a novel, simple and effective means for regulating the supply of ink to the nib.

I attain the above and other objects by a mechanical construction which will be hereinafter specifically described by reference to the drawings wherein,

Figure 1 is a longitudinal view of the entire pen, the casing, collar and connecting member being shown in section.

35 Fig. 2 is a sectional end view of the pen on the line 2—2 of Fig. 1.

Fig. 3 is a longitudinal sectional view of a section of the pen taken at right angles to the view shown in Fig. 1.

40 Fig. 4 is a side elevational view of the connecting member 3.

Fig. 5 is a detail plan view of the nib.

Fig. 6 is a front end view of the nib.

Fig. 7 is a rear end view of the nib.

45 Fig. 8 is a view of the clamping surface of one of the jaws.

Fig. 9 is a sectional view of the two complementary, jaw sections.

Fig. 10 is a view of the valve 11.

50 Fig. 11 is a view of a section of the pen showing the reduced portion of the valve stem.

Referring to the drawings, wherein like numerals designate like parts in the several views, 1 designates a hollow casing or reservoir internally threaded, at one end for the

reception of a connecting member, 3, circumferentially threaded at both sides of an annular flange, 4, knurled upon its periphery so as to permit a tight grip when inserting 60 the connecting member into the end of the casing. One end, 5, of the connecting member, 3, is adapted to enter the casing and engage the threads therein, the flange 4 being used for a grip when screwing the end 5 into the casing. The other end, 6, of the connecting portion is slotted to receive the jaws 7, 7' which in turn hold between them the nib or pen point 8. A collar, 9, with a 65 threaded and slightly tapered bore fits over the slotted end of the connecting member and clamps the same about the jaws, which are corrugated upon their inner surfaces for a purpose hereinafter set forth. Each of these complementary jaw sections gradually 70 thickens in cross-section from its lower end toward its base and is provided with a smooth and semi-circular outer surface to snugly conform the curve of the inner circumference of the connecting member. 75

The nib, or pen point, 8, is at one end provided with a plurality of longitudinal slits extending about $\frac{1}{4}$ of the length of the nib so that but a slight pressure exerted upon the nib in writing, will broaden the same 80 at its writing point and permit the making of a mark of a width in proportion to the pressure exerted.

This nib, 8, is of the same width in cross-section from its writing point to its upper 90 end and beginning with the end of the slits, is corrugated upon both faces. These corrugations and the raised portions upon the inner surfaces of the jaws provide suitable channels for the passage of the ink from the casing to the nib which, being corrugated upon both of its faces, is fed with the fluid upon both sides, thus insuring a supply of ink in sufficient quantity for the mark which is to be produced.

100 The upper end of the casing, 1, is provided with an opening into which is fitted a valve stem, 10, extending longitudinally through the casing and which is substantially the same diameter as the opening, so as to snugly fit into said opening. This stem is provided at one end with a disk valve 11, shown in the drawings to be peripherally serrated in order to permit the ink to pass from the reservoir to the opposite side of the valve 105 11, in a percolating drop flow, rather than in a steady and unbroken stream. The serra-

tions are not necessary for the operation of my device but improve the feed to the pen point from the reservoir. Upon the upper end of the valve stem, 10, is provided an annular flange 12, which serves as an abutment for a spiral spring, 14, wound around the stem and pressing at its upper end against the top 13, of the casing. The valve stem at this end is threaded to receive a nut, 15, internally threaded and formed with a concave face 16 to permit the entrance of air into the casing. In order to permit the air to reach the concave face of the nut, this nut may be provided with an air passage of any suitable character either in the wall or as herein shown at 17 through the top of the nut. The valve stem 10, is gradually reduced in diameter at a point near its upper end, as shown in Fig. 11, so that when the stem is drawn up the reduced portion coming into the opening permits the entrance of air to the casing. The advantage of gradually reducing the stem from its upper end toward the valve head is apparent for the higher the stem is drawn, up to a certain limit, the larger will be the space between the stem and the edge of the casing around the opening and hence the more air admitted.

50 The operation of my device is as follows: The spring 14 is normally tensioned to keep the valve disk, 11, seated upon the top of the jaws 7, 7' thereby covering up the channels between the jaws and the faces of the nib. When the nut, 16, is turned to the right, it draws up the stem 10 and disk 11, makes more space between the top of the jaws and the disk, 11, and consequently permits a freer flow of ink to the nib from the casing. The raising of the valve also permits an increased supply of ink to the pen point by bringing the reduced portion of the stem 10 into the opening and thereby permitting the entrance of air to the reservoir. 45 The higher up the stem is drawn a reduced portion of still smaller diameter is brought into the opening and consequently a larger opening is provided for the entrance of air.

55 A further means for adjusting the passage of marking fluid to the pen point is provided in the collar, 9, upon the slotted portion of the connecting member 3. The bore of this collar being tapered the further upon the connecting member it is screwed, the greater becomes the pressure upon the jaws which are forced to take a tighter bite upon the pen. In this way, the channels for the ink, which are between each jaw and the pen, are decreased or increased in 60 size depending upon the direction the collar, 9, is turned.

65 It is obvious that when it is desired to fill my pen, the connecting portion is simply removed from the casing by grasping the flange 4, to unscrew the connecting member

and the ink then poured into the casing with a suitable filler.

This invention is susceptible to various minor modifications and changes which would be within the scope of my claims. 70

What I claim is:—

1. A fountain pen having a casing forming an ink reservoir, a connecting member adapted to be connected to one end of said casing, jaws held within said connecting member, a nib held by said jaws, and means on said connecting member to regulate the bite of the jaws upon the nib and thereby regulate the flow of marking fluid. 75

2. A fountain pen having a casing forming an ink reservoir, a connecting member adapted to be connected to one end of said casing, jaws having corrugated inner surfaces held within said connecting member, a nib held by said jaws, and a collar on said 85 connecting member to adjust the bite of the jaws upon the nib and thereby regulate the flow of marking fluid.

3. A fountain pen having a casing forming an ink reservoir, a connecting member 90 adapted to be inserted in one end of said casing, said connecting member being threaded and having one slotted end, jaws having corrugated inner surfaces held within said connecting member, and a collar, on 95 said connecting member having a tapered bore to adjust the bite of the jaws upon the nib and thereby regulate the flow of marking fluid.

4. A fountain pen having a casing forming an ink reservoir, a connecting member adapted to be connected to one end of said casing, pen holding members held within said connecting member, and a nib having a writing point provided with a plurality 100 of longitudinal slits and having corrugations upon each face beginning with the upper ends of the slits and extending to the base of the pen whereby ink may be fed to the writing point upon both faces 105 of the nib.

5. A writing pen having a casing forming an ink reservoir, a connecting member adapted to be connected to one end of said casing, said connecting member having a 110 slotted end, jaws held within the slotted end of said connecting member, a nib having longitudinal slits at its writing point and corrugated upon both faces held between said jaws and a collar upon said connecting member to vary the bite of the jaws upon the nib and thereby regulate the feed of the ink. 115

6. A writing pen having a casing, a connecting member having at its central portion an annular flange and adapted to be connected to one end of said casing, said connecting member having one slit end, jaws having corrugated inner surfaces held within the slit end of said connecting member, 120

130

- a nib having longitudinal slits at its writing point and corrugated upon both faces held between said jaws, and a collar having a tapered bore upon said connecting member 5 to vary the bite of the jaws upon the nib and thereby regulate the flow of marking fluid.
7. In a fountain pen having a casing, a connecting member, jaws within said connecting member, a nib having a plurality of 10 longitudinal slits at its point and corrugations upon both faces whereby the pen may be fed with writing fluid upon both of its faces.
8. A fountain pen having a casing with 15 an opening in the top thereof, a connecting member adapted to be inserted in the lower end of the casing, jaws held within said connecting member, a nib held between said jaws, a valve within said casing and a valve stem extending through the opening in the 20 top of the casing and adapted to close said opening, said stem having an intermediate portion gradually reduced in diameter from its top toward the valve, and a nut upon the end of said valve stem for raising said 25 valve and bringing the reduced portion of the stem into said opening whereby air may be admitted to the casing.

In testimony whereof I have hereunto set my hand.

FREDERICH W. KUEHN.
